UNITED STATES PATENT OFFICE.

DAVID A. ALEXANDER, OF ROCHESTER, NEW YORK.

ALARM DEVICE.

Application filed February 2, 1923, Serial No. 616,580. Renewed November 27, 1923.

To all whom it may concern:

Be it known that I, DAVID A. ALEXANDER, a citizen of the United States, residing at Rochester, in the county of Monroe and 5 State of New York, have invented a new and Improved Alarm Device, of which the following is a specification.

My invention relates more particularly to that class of alarm devices in which fluid 10 under pressure is the motive force for operating a gong striking member such, for instance, as water motor alarms used in connection with automatic sprinkler systems, although I do not limit the invention 15 to an alarm device for this purpose only as it will readily be understood from the following description and accompanying drawings that an alarm device constructed in accordance with the invention may be equally 20 adaptable for use on street cars or automobiles, in which event compressed air or exhaust gases from an explosive engine would be used as the motive force.

Water motor alarms used in connection 25 with automatic sprinkler systems, and the type now in general use, consists of a water wheel encased in a housing, an operating shaft, bearings and a stuffing box, a universal joint to overcome discrepancies in alignment 30 between the water wheel and gong, an outer sleeve enclosing the operating shaft, such shaft extending through a building wall, a gong, striker arms on said shaft, hammers on the striker arms, and a housing 35 for the gong together with other essentially necessary parts. Past experience has proven that water motor alarms such as just above described often fail in operation, after long periods of inaction, owing to corrosion 40 of parts, and also fail in operation because of the liability of erecting the motor and gong out of alignment and of the tendency of such parts to get out of alignment through settling of the building wall. This 45 type of alarm is also expensive to manufacture and install.

An object of this invention is to provide a water motor alarm to be used in connection with automatic sprinkler systems which 50 will be extremely simple in construction, of few parts, positive of operation at all times and under any and all conditions, besides being inexpensive to manufacture and install.

Another object of the invention is to provide a water motor alarm that will be equal-

ly effective whether mounted on the outside or inside of a building wall.

Another object of the invention is to provide an alarm device of the character described employing a gong and in which the motor mechanism is enclosed by the gong.

Another object of the invention is to provide an alarm device having but one movable part.

A further object of the invention is to provide an alarm device in which motor mechanism comprises a tubular member bent into approximately circular form and having a striking member in the form of a ball adapted to continuously circulate through the tubular member by the action of fluid under pressure injected into the tubular member.

And, a still further object of the invention is to provide in an alarm device a sounding member in the form of a steel tube bent approximately in circular form with the ends of the tube separated, and a striking member comprising a ball adapted to continuously circulate through the tubular member by the action of fluid under pressure injected into the tube.

To these and other ends the invention consists of certain parts and combinations of parts all of which will be fully brought out in the following description and particularly defined in the appended claims.

The accompanying drawings illustrating the invention are as follows:

Figures 1 and 2 are side and face views, respectively, with parts broken away, of a water motor gong made in accordance with my invention and adapted for use in connection with automatic sprinkler systems.

Fig. 3 is a part side view and part vertical sectional view of a water motor gong in which the motor mechanism is mounted inside the gong, and showing the gong on the inner face of a building wall.

Fig. 4 is a face view, with parts broken away, of the device shown in Fig. 3.

Fig. 5 is a sectional detail on the line 5—5, Fig. 4.

And, Fig. 6 is a face view of a modification of the invention adaptable for use as an alarm device on vehicles.

In the drawings, similar reference numerals refer to similar parts throughout the several views.

Referring first to Figs. 1 and 2, the numeral 1 represents a supporting plate which

may be secured by any suitable retaining devices, not shown, to a building wall. Projecting outwardly from this plate 1 is a stud 2 on which a circular gong 3 is mounted and held in place by means of a cap nut 4 on the threaded outer end of the stud.

The motor mechanism comprises a cylinder in the form of a tubular flange 5 integral with a web or plate 6 mounted on a stud 7 and held in place against a shoulder on the stud by means of a cap nut 8. The bore in the cylinder or tubular flange 5 is continuous and although approximately a circle it really has two angularly disposed portions 10 and 11 tangential to a circular portion 9. Substantially diametrically opposite the juncture of the angular portions 10 and 11 of the bore the cylinder wall is cut away as at 12 to receive a peripheral portion 20 of the gong 3, in the manner clearly indicated. In line with the tangential portion 10 of the bore is a restricted opening 13 in the cylinder wall having communication with a nipple 14 threaded into the wall and which in turn has threaded connection with an inlet pipe 15 leading from the water supply pipe at a point above the automatically operable valve for controlling the admission of water into a sprinkler system. The cylinder wall along the tangential portion 11 and that part of the curved portion 9 beyond the opening 12, with respect to the inlet 13, is provided with a discharge in the form of a plurality of lateral openings 16. The striking member is a ball 17 normally lying against the inlet opening 13 and adapted by the force of water under pressure entering the cylinder through the opening 13 to be shot along the tangential portion 10, around the curved portion 9 and to return through the tangential portion 11, to its starting point. So long as the water is entering the cylinder the travel of the ball 17 will be continuous and each time it passes the wall opening 12 will strike the periphery of the gong owing to the tendency of the ball in traversing the circular portion to leave the curve on a straight line tangent to the curve, this being a fixed law of motion. The water in the cylinder will escape some through the opening 12 but mostly through the discharge openings 16, and the action of the water jet from the inlet opening 13 will tend to effect a suction in the cylinder portion 11 so that the ball is drawn into the path of the jet. In Fig. 2 a plurality of balls 17 are shown but practice has demonstrated that one ball is sufficient and that it will hit the gong forceful blows with trip hammer rapidity.

The gong and the motor mechanism are enclosed by a housing comprising two members 18 and 19 formed with flanges 20 and 21, respectively, which abut the marginal edge of the supporting plate 1 and are se-

cured thereto by screws 22. The upper housing member 18 has its front wall offset at 18^a so as to overhang the front upper edge of the member 19 and provide a sound opening. Water discharged from the cylinder escapes from the housing through a drain pipe 19^a.

In the modification of the invention shown in Figs. 3, 4 and 5, the supporting plate 1^a is secured to the inner face of a building wall 23 and has openings 24 opposed to an opening 25 in the wall, such latter opening preferably being closed on the exterior of the wall by any suitable screen covering 26. This plate 1^a carries a stud 2^a on which a circular gong 3^a is mounted in a manner similar to the gong 3 on the stud 2, while the motor mechanism is covered by the gong and the ball striking member 17^a is adapted to engage a projection 27 formed on the inner periphery of the gong.

The motor mechanism, in this instance, comprises a casting mounted on a stud 7^a and formed by a tubular portion 28 having an approximately circular path of travel for the ball 17^a, such tubular portion being integral with a double web or spaced plates 29. The return bend of the tubular wall has the portion thereof between the plates 29 cut away so as to discharge the water after passing the opening 12^a into a chamber 30 between the plates 29 and from this chamber the water escapes through a pipe 31 and is directed into a drain pipe 32 leading from a housing 33 which, in this instance, is a one piece member secured to the supporting plate 1^a in the same manner as the housing members 18 and 19 are secured to the plate 1. The cylinder is provided with an inlet opening 13^a and an inlet connection 15^a as and for the same purpose as the inlet connection shown in Fig. 2.

In Fig. 6 there is shown a modification of the invention adaptable for an alarm device on vehicles such as street cars or automobiles. The numeral 34 represents a sounding member in the form of a tubular chime bent to approximate a circle but really having a curved portion 9^a and two short angularly disposed portions 10^a and 11^a tangential to the curved portion, the ends of the tube lying in the line of the portion 11^a and being slightly spaced apart to provide a discharge opening for the fluid under pressure and to permit a vibration of the tube when the ball 17^b strikes the wall of the tube at the points X. With this modification compressed air would likely be used as the motive force although exhaust gases from an explosive engine may be employed. An inlet for the motive fluid is indicated at 13^b which communicates through the nipple connection 14^b with a fluid supply pipe 15^b, if desired a valve 35 being located in the pipe line to deflect fluid through the lateral 130

connection 14^b. The continuous circulating action of the ball 17^b in this instance will be the same as in the modifications shown in Figs. 2 and 5. The tubular member 34 may 5 be formed with an attaching plate or projection 36 for securing it to a fixed part of a vehicle indicated at 37.

It is believed that from the above description the construction and operation of the 10 alarm device is sufficiently clear to call for no further explanation.

What I claim is:

1. In an alarm device, a piston comprising 15 a striking member, a cylinder having an approximately circular path of travel for the striking member, sounding means projecting into the path of the striking member, an inlet to the cylinder for fluid under pressure, and a discharge opening in the cylinder 20 wall.

2. In an alarm device, a piston comprising 25 a striking member, a cylinder having a bore formed with a circular portion and two angular portions tangential to the circular portion, such bore comprising an endless path of travel for the striking member, sounding means projecting into the path of the striking member, an inlet to the cylinder for fluid under pressure, and a discharge 30 opening in the cylinder wall.

3. In an alarm device, a striking member, 35 a cylinder having an approximately circular path of travel for the striking member and an opening in the cylinder wall, an inlet to the cylinder for fluid under pressure, a sounding device in the path of the striking member as it passes the said opening, and an exhaust opening in the cylinder wall.

4. In an alarm device, a striking member, 40 a cylinder having an approximately circular path of travel for the striking member and an opening in the cylinder wall, an inlet to the cylinder for fluid under pressure, a circular gong having a periphery adapted to be 45 engaged by the striking member as the latter passes the said opening, and an exhaust opening in the cylinder wall beyond the said first named opening.

5. In an alarm device, a tubular member 50 formed into an approximate circle and having an opening in the wall thereof, a ball in said tube, an inlet in said tube for fluid under pressure and having a restricted opening, sounding means adjacent said wall opening adapted to be struck by the ball as it passes the said opening, and a discharge opening in the tube beyond the said wall opening and of greater area than said inlet.

6. In an alarm device, a supporting 60 plate, a striking member, a cylinder mounted on said plate and having an approximately circular path of travel for said striking

member and an opening in the cylinder wall, a gong mounted on said plate having a periphery adapted to be engaged by the 65 striking member as the latter passes the said opening, an inlet to the cylinder for fluid under pressure, an outlet from the cylinder beyond the said opening, a housing for the gong and cylinder, and a drain leading from 70 the housing.

7. In an alarm device, a supporting plate, a stud carried by said plate, a plate mounted on said stud and an approximately circular tubular flange formed on such plate, a ball 75 in said tube, an inlet in said tube having a restricted opening for fluid under pressure and an opening in the tubular wall, a gong mounted on said supporting plate having a periphery adapted to be engaged by the ball 80 as the latter passes the said wall opening, an outlet from the tube beyond the said wall opening of greater area than said inlet opening, a housing for the gong and the tubular flanged plate, and a drain leading 85 from the housing.

8. In an alarm device, a supporting plate, a tubular member mounted on the plate and formed into an approximate circle, such member having an opening in the wall 90 thereof, a ball in said tube, an inlet in the tube for fluid under pressure and an outlet in the tube beyond the said wall opening, a gong mounted on the supporting plate to 95 cover the tubular member, means on a periphery of said gong adapted to be engaged by the ball as it passes the said wall opening, a housing for the gong, and a drain leading from the housing.

9. In combination with a building wall 100 having an opening therethrough, a supporting plate on the inner face of the wall having an opening within the area of said wall opening, a tubular member mounted on said plate, such member having an opening in the wall thereof, an inlet in said tubular member for fluid under pressure, a ball in said tube, an outlet in the tube beyond the said wall opening, sounding means adjacent the said wall opening adapted to be engaged by 105 the ball as the latter passes said opening, a housing for the gong and sounding means, and a drain leading from the housing.

10. In an alarm device, an approximately 110 circular cylinder having an inlet and a discharge opening, a spherical piston comprising a striking member adapted to continuously circulate through the cylinder by the action of fluid under pressure injected into the cylinder through the said inlet, and 115 sounding means projecting into the path of the striking member.

DAVID A. ALEXANDER.
